[57] ABSTRACT

Compounds of the formula

where X and Y vary independently and are F, H, NO₂ and CH₃ are prepared by reacting an alcohol of the formula

with dimethyl acetylenedicarboxylic acid to yield

which is then converted to the desired product. The compounds are useful as plasticizers in explosive and propellant compositions.

4 Claims, No Drawings

**2-SUBSTITUTED-2,2-DINITROETHOXY-FUMARIC
ACID
BIS(2-SUBSTITUTED-2,2-DINITROETHYL)ESTER**

BACKGROUND OF THE INVENTION

This invention relates generally to plasticizers and more particularly to high energy carboxylic acid esters and to a process for the preparation thereof.

The use of plasticizers in both explosive and propellant compositions is widely known. There has long been a search for plasticizers which besides being thermally stable have a relatively high energy which can be released on detonation so that the propellant or explosive composition will have maximum energy per unit weight. It is also often desirable to have plasticizers which are miscible with other plasticizers so that mixtures of plasticizers can be used in a composition. The use of such mixtures will yield a product with a lower melting point than any of the components individually and will therefore enhance low-temperature properties of the system.

SUMMARY OF THE INVENTION

Accordingly, it is an object of this invention to provide high energy, thermally stable esters of fumaric acid.

Another object of this invention is to provide plasticizers which can be used in propellant and explosive compositions.

Still another object of this invention is to provide a method for the preparation of esters of fumaric acid.

Another object of this invention is to provide chemical intermediates which can be used to prepare esters of fumaric acid which are useful as plasticizers in propellant and explosive compositions.

These and other objects of the invention are accomplished by providing compounds of the formula

where X and Y vary independently and are selected from the group consisting of F, H, NO₂ and CH₃ which are prepared by esterifying acids of the formula

with alcohols of the formula

by any of the conventional esterification techniques.

**DESCRIPTION OF THE PREFERRED
EMBODIMENTS**

The esters of fumaric acid are prepared, for example, according to the following reaction sequence:

The desired fumaric acid esters of this invention are obtained by a multi-step synthesis. First, dimethyl acetylenedicarboxylate is reacted with an alcohol of the formula

where Y represents F, H, NO₂ and CH₃ in pyridine and a solvent such as methylene chloride at about 0°–5°C for about 1 hour to produce

which is obtained after a conventional work-up comprising washing, drying, filtering and distilling. This

product is then converted to the diacid by refluxing in water with HCl, followed by filtering, chilling and re-crystallizing.

50 The diacid is then converted to the monoester by reacting the diacid with an alcohol of the formula

60 where X represents F, H, NO_2 and CH_3 . This reaction is carried out in the presence of polyphosphoric acid at a temperature between 85°-100°C. Upon quenching after about 7 hours the product separated out.

Conversion to the desired diester is effected by converting the monoester to the monoester-monoacid chloride which is effected by contacting the monoester with thionyl chloride in the presence of pyridine at reflux temperature and then converting said monoester-monoacid chloride by contacting with the appropriate alcohol.

The general nature of the invention having been set forth, the following examples are presented as specific illustrations thereof. It will be understood that the invention is not limited to these specific examples but is susceptible to various modifications that will be recognized by one of ordinary skill in the art.

EXAMPLE 1
DIMETHYL α (2-FLUORO-2,2-DINITROETHOXY) FUMARATE

To a solution of 7.9g (0.1 mole) of pyridine in 75 ml of methylene chloride was added dropwise at 3°-5°C with stirring and cooling over a period of 15 min. a mixture of 7.7g (0.05 mole) of 2-fluoro-2,2-dinitroethanol and 7.1g (0.05 mole) of dimethyl acetylenedicarboxylate. A mildly exothermic reaction was observed and the reaction mixture turned deep orange-red with the color gradually intensifying. The reaction mixture was kept at 0°-5°C for an additional 60 minutes and then was washed with a cold solution of 11g of sulfuric acid in 50 ml of water. The methylene chloride solution was dried, filtered, concentrated and the residual material was degassed at 85°C/0.1 mm to give 14.3g of dark viscous oil. An analytical sample of material was obtained by distillation in a molecular still at 100°-105°C/50 μ . The distillate solidified at room temperature into a white solid m.p. 42°-44°C. The product was dimethyl 2-fluoro-2,2-dinitroethoxyfumarate.

EXAMPLE 2
(2-FLUORO-2,2-DINITROETHOXY) FUMARIC ACID

A 1 liter flask was charged with 300 ml concentrated hydrochloric acid, 300 ml water and 87g dimethyl α (2-fluoro-2,2-dinitroethoxy) fumarate. The mixture was stirred magnetically and heated in an oil bath at or near reflux for 4 hours. The hot mixture was filtered through filter-aid to remove some black decomposition products. The filtrate was chilled at -20°C for 1 hour, and the product separated by filtration and washed with cold 6N HCl. The filtrate was concentrated to a volume of 175 ml, 50 ml concentrated HCl was added, and following storage at -20°C an additional 14.5g of acid was isolated. Total yield 42.5g. 28g of crude acid was dissolved with heating in 100 ml water, treated with decolorizing charcoal, filtered through filter-aid, and precipitated by additional of 100 ml concentrated HCl followed by cooling. The colorless solid melted at 194°-5°C.

EXAMPLE 3

MONO (2-FLUORO-2,2-DINITROETHYL) ESTER OF α -(2-FLUORO-2,2-DINITROETHOXY) FUMARIC ACID

α -(2-Fluoro-2,2-dinitroethoxy) fumaric acid (1.15g, 0.0043 mole and 5.5g polyphosphoric acid in a 25 ml flask were immersed in an oil bath at 90°C. In portions, 2-fluoro-2,2-dinitroethanol (1.9g, 95% pure; 0.0117 mole) was added with essentially no exotherm. The oil bath was maintained at 85°-100°C and the mixture was stirred occasionally by hand. After 6½ hours the reaction mixture was quenched in ice and water, and the product precipitated in fine crystals and small lumps on stirring. The lumps were broken up manually. After storage under refrigeration overnight, the crude, light tan product was filtered, washed with water, first dried in air and then finally dried in a vacuum desiccator. The product melted at 114.5°-116°C. The product may

be further purified either by recrystallization from chloroform carbon tetrachloride, or by solution in sodium bicarbonate followed by filtration and acidification.

EXAMPLE 4

BIS(2-FLUORO-2,2-DINITROETHYL) ESTER OF α (2-FLUORO-2,2-DINITROETHOXY) FUMARIC ACID

10 A Acid Chloride
Two grams (0.005 mole) of the mono-ester, purified by base-acid reprecipitation, were partly dissolved by heating in 22 ml chloroform (kept over calcium chloride). At 45°C, 2.4g thionyl chloride was added with no indication of any reaction. At 30°C, 10 drops of pyridine were added and the mixture heated to reflux for 4 hours. Homogeneity was never obtained.

15 The mixture was cooled to room temperature and filtered through filter aid to remove a very small quantity of brown particles. The solvent and excess thionyl chloride were removed under vacuum, leaving the product as a dark brown, viscous residue.

B. Esterification

20 The crude acid chloride from above was dissolved in 10 ml methylene chloride and 1.23g 2-fluoro-2,2-dinitroethanol (about 0.008 mole) and a spatula-tip of anhydrous aluminum chloride were added. The mixture was refluxed for 4½ hours. After cooling, insolubles 25 were removed with filter-aid and the filtrate washed with 5% aqueous sodium bicarbonate and then with water. The solution was dried briefly over silica gel, and the solvent removed under vacuum, ultimately for 10-15 minutes at 40°C/0.1mm. The residue, a viscous brown oil, was stored in the freezer. A few crystals 30 appeared after 2 days, and these were saved as seeds. The main batch was dissolved in 10 ml toluene, giving a clear, light yellow solution. The addition of 4.5 ml cyclohexane caused a small precipitate of dirty appearance which was filtered off. A further portion of cyclohexane (2.5 ml) was added, followed by seed crystals. The mixture was stored overnight in the freezer and the product filtered and washed, first with cold solvent mixture, then with hexane at 20°C. The dried product 35 consisted of nearly colorless crystals; weight 0.86g; m.p. 63°-4°C.

40 Similarly when esters of the general formula

50 wherein X and Y are other than F, are desired the appropriate alcohol in the above reactions may be used to obtain them.

55 Obviously numerous modifications and variations of the present invention are possible in light of the above teachings. It is therefore to be understood that within the scope of the appended claims the invention may be practiced otherwise than as specifically described herein.

What is claimed as new and desired to be secured by Letters Patent of the United States is:

1. A fumaric acid ester of the formula

wherein X and Y vary independently and are selected from the group consisting of F, H, NO₂ and CH₃.

2. A compound according to claim 1 wherein X and Y both represent F.

3. A method of preparing the compounds of claim 1 comprising:

1. contacting in solution dimethyl acetylenedicarboxylic acid with an alcohol of the formula

in the presence of pyridine at about 0°-5°C to produce

2. contacting in solution the product of step 1 with HCl to produce

3. contacting in solution the product of step 2 with an alcohol of the formula

in the presence of polyphosphoric acid to yield the mono ester of the product of step 2;

4. contacting in solution the mono ester of step 3 with thionyl chloride in the presence of pyridine to obtain the mono ester - mono acid chloride, and

5. contacting said mono ester - mono acid chloride of step 4 with an alcohol of the formula

4. The process of claim 3 wherein X and Y are both F.
